UNITED STATES PATENT OFFICE.

ARCHIE W. STEELE, OF BLOOMFIELD, NEW JERSEY, ASSIGNOR TO WILFORD J. HAWKINS, OF MONTCLAIR, NEW JERSEY.

ELECTRIC FUSE.

1,396,297.

Specification of Letters Patent. Patented Nov. 8, 1921.

Application filed September 24, 1919. Serial No. 325,882.

To all whom it may concern:

Be it known that I, ARCHIE W. STEELE, a subject of the King of Great Britain, residing at Bloomfield, in the county of Essex, 5 State of New Jersey, have invented certain new and useful Improvements in Electric Fuses; and I do hereby declare the following to be a full, clear, and exact description of the invention, such as will enable others 10 skilled in the art to which it appertains to make and use the same.

This invention relates to fuses employed in safeguarding electric systems and more particularly to such a device in which the 15 fuse element is readily removable and replaceable.

The object of the invention is to produce a fuse of simple and relatively inexpensive construction and in which a burned out fuse 20 element may be replaced with the utmost facility, the element being, nevertheless, securely fastened within the fuse body with its ends firmly gripped, and held in electrically conductive relation with metal parts 25 adapted to be connected to a circuit.

Further objects and advantages of the invention will be apparent as it is better understood by reference to the following specification, when read in connection with the 30 accompanying drawing illustrating the preferred embodiment of my invention, it being understood that numerous details of the structure may be modified without departing from the essentials of the structure. In 35 the drawing,

Figure 1 is a side elevation of a fuse;

Fig. 2 is a longitudinal section, on the line 2—2 of Fig. 4, illustrating my invention;

Fig. 3 is a plan view of a fuse element; 40 Fig. 4 is an end elevation of the fuse;

Fig. 5 is a detail in section on the line 5—5 of Fig. 6; and

Fig. 6 is an end elevation of a slightly different form of my invention slightly different from that illustrated in Figs. 1 to 4 inclusive.

In general structure my improved fuse conforms substantially to established practice, having a body 5 consisting of a tube of vulcanized fiber, or other suitable insulating material, carrying metal ferrules 6 at opposite ends, the edges of the ferrules being 50 preferably crimped over the ends of the tube 55 so that they are held securely in place. The

ferrules are adapted to contact with the usual clips (not shown) whereby the fuse is connected to an electric circuit. A fuse element 7, which may be of the form illustrated in Fig. 3 and of any usual or suitable material, is arranged within the tube 5 diagonally thereof and with its ends in contact with the opposite ferrules 6. One projecting end of the fuse element may be stamped, if desired, with the capacity of the fuse. 60 65

To hold the fuse element 7 securely in position, I have provided caps 8, adapted to be inserted within the ends of the tube 7, thereby holding the extremities of the fuse element in close contact with the inturned 70 edges of the ferrules 6. Preferably the caps 8 are slotted at 9 to render them more resilient, thus permitting insertion and removal with facility and insuring retention of the fuse element when the fuse is in use. 75

Fuses of the smaller dimensions usually carry relatively thin fuse elements which do not interfere in any way with the insertion and removal of the caps 8. In the larger sizes, however, the thickness of the fuse element is material and to accommodate my invention to the larger sizes, I preferably employ a construction as illustrated in Figs. 5 and 6. The body of the fuse in this form of my invention comprises a tube 10 of insulating material, with ferrules 11 having crimped edges 12 as previously described. A fuse element 13 is disposed within the tube diagonally thereof and its extremities are held in contact with the crimped ends 12 80 85 of the ferrules 11 by caps 14, which are preferably slotted at 15 to give them resiliency. The caps 14 are, however, flattened at one side as indicated at 16 (Fig. 6) to allow for the thickness of the fuse element 13, and 90 may thus be inserted and removed without interference by the fuse element, which is gripped between the flattened surfaces of the caps and the inturned edges of the ferrules. 95

In removing and replacing fuse elements 100 in fuses of the character described, it is necessary merely to pry out or otherwise remove the end caps, thus freeing the fuse element. A new fuse element may be as readily inserted and the caps replaced, the entire 105 operation requiring but a few moments.

The extreme simplicity of the construction is at once apparent. The parts, with the exception of the insulating tube, may be 110 readily stamped from sheet metal, or formed

in some equally simple manner in accordance with well known practice. The parts are interchangeable and may be assembled with great rapidity by relatively unskilled labor. I am thus enabled to produce a fuse having a replaceable fuse element at a relatively low cost, and the fuse thus produced may be used almost indefinitely by the simple replacement of the fuse element as may become necessary. My invention has, therefore, marked economic advantages and is adapted to replace fuses of the common type which become worthless when the fuse element is burned out by excessive flow of current therethrough.

Various changes and modifications may be made in the structure as illustrated in the drawing and hereinbefore described without departing from the spirit and scope of the invention as defined in the accompanying claims.

I claim:

1. An electric fuse, comprising, a hollow body of insulating material, metallic ferrules at the ends of said body having inturned edges engaging the inner surface of the hollow body, a flat fuse element within said body and resilient friction caps slightly smaller in external diameter than the internal diameter of the hollow body engaging said inturned edges and firmly gripping the extremities of said fuse element in electrical contact therewith.

2. An electric fuse, comprising, a hollow body of insulating material, spaced metallic

ferrules on said body having their edges crimped over the ends thereof, a fuse element within said body, and having metal friction caps slightly smaller in external diameter than the internal diameter of the hollow body adapted to be inserted in the ends of said body to hold said fuse element in electrical contact with the crimped edges of said ferrules.

3. An electric fuse, comprising a hollow body of insulating material, metallic ferrules at the ends of said body having inturned edges engaging the inner surface of the hollow body, a flat fuse element diagonally disposed within said body and friction caps disposed within the ends of said body to grip and hold said fuse element in contact with said inturned edges, said caps being slotted to increase the resiliency and thereby facilitate insertion and removal thereof.

4. An electric fuse, comprising, a hollow body of insulating material, metallic ferrules at the ends of said body having inturned edges engaging the inner surface of the hollow body, a fuse element diagonally disposed within said body and friction caps disposed in the ends of said body to hold the extremities of said fuse element in electrical contact with said inturned edges, said caps being flattened at one side to permit insertion thereof in contact with fuse elements of substantial thickness.

In testimony whereof I affix my signature.

ARCHIE W. STEELE.
